INVENTOR.

Edward H. St. Ongé.

BY

Thos. S. Kennedy
ATTORNEY

UNITED STATES PATENT OFFICE

EDWARD H. ST. ONGE, OF DETROIT, MICHIGAN

WOODWORKING TOOL

Application filed August 13, 1928. Serial No. 299,216.

My invention relates to a new and useful improvement in a woodworking tool adapted for forming dowels which may be utilized for covering screw and nail heads which are driven into wood, the dowel serving as a covering to prevent entry of the elements to the nail or screw head, and to take the place of putty or similar covering which is now used.

10 It is an object of the present invention to provide a tool whereby these dowels may be economically manufactured and to provide a tool which will be simple in structure, highly efficient in use, and easily and quickly operated.

15 Another object of the invention is the provision of a tool whereby the wood cutting member may be easily and quickly removed and replaced with another when necessary.

20 Other objects will appear hereinafter.

The invention consists in the combination and arrangement of parts hereinafter described and claimed.

The invention will be best understood by 25 a reference to the accompanying drawings which form a part of this specification and in which,

Fig. 1 is a side elevational view of the invention with a part broken away and a part 30 shown in section.

Fig. 2 is an enlarged fragmentary sectional view taken on line 2-2 of Fig. 1.

The invention comprises the stem 7 which may be connected in a bit stock or other suitable tool for effective rotation therewith. 35 The lower end of this stem 7 is provided with a socket to form the tubular portion 8 which is sharpened at its end as at 9 to effect a cutting contact with the wood. Slidably 40 mounted in the socket 8 is a rod 10 having the reduced stem 11 which carries a cutting head 12. Fixedly mounted on the stem 7 is a collar 13 engaging against which is one end of a coil spring 14, the other end of which 45 engages the collar 15 having a notch 16 formed at diametrically opposite points for reception of the pin 17 which is projected through the rod 10 and which is adapted to ride in the slot 18 formed in the tubular portion of the 50 stem 7, this pin 17 projecting beyond the pe-

riphery of the stem 7 and being of the same length as the diameter of the collar 15.

In operation, the cutting head 12 is engaged against the wood over the nail or screw head and rotated, upon rotation of the stem 7 so that as the sharpened edge 9 of the tubular portion of the stem engages the wood, a clear, well-defined recess is provided in the wood above the screw or nail which has been countersunk in the usual manner. 60 When the cutting head 12 engages the wood, the desired drilling will be effected and when the cutting edge 9 is brought into engagement with the wood the hole drilled is neatly drilled, this cutting edge 9 removing all burs 65 which may be drawn out by the cutting head 12. When this hole is provided a dowel formed from wood may be placed therein and a neat filling of the opening effected, the dowel being selected on account of the resemblance of its grain with the grain of the wood in which it is to be located, so that the presence of the nails or screws may be completely concealed. 70

By having the head 12 normally projected 75 beyond the tubular portion of the stem and having the rods slidably in the tubular portion or socket, the operator may, when using the device by exerting downward pressure on the member 7, bring the cutting edge 9 into 80 contact with the material worked upon at any determined stage of operation so that the cutting edge 9 may perform its function when the hole is drilled by the cutting element 12 at any determined depth. 85

While I have illustrated and described the preferred form of my invention, I do not wish to limit myself to the precise details of structure shown but desire to avail myself of such variations and modifications as come 90 within the scope of the appended claims.

Having thus described my invention what I claim as new and desire to secure by Letters Patent is:

1. A tool of the class described comprising 95 a stem formed tubular at one end and sharpened to provide a cutting edge; a rod slidably mounted in said end, said end having an axially extending slot formed therein; a pin projecting diametrically outwardly from the pe- 100

riphery of said rod and engaging in said slot; a cutting member carried on the end of said rod, and a spring embracing said stem for normally retaining said rod in outwardly thrust position relatively to said tubular portion to normally retain said cutting member exterior of said stem.

5. A tool of the class described comprising a stem having a socket formed in one end, the edges of said end being sharpened; a rod slidably mounted in said socket, said stem having oppositely disposed longitudinal extending slots communicating with said socket; a pin projecting peripherally in said rod and 10 engaging in said slots; an engagement member fixedly mounted on said stem; a collar embracing said stem and slidably thereon and engaging the ends of said pin; and a spring positioned on said stem and engaged at one 15 end with said engagement member and at the other end with said collar for normally retaining said pin moved to one end of said slots.

6. A tool of the class described comprising a stem having a socket formed in one end, 20 the edges of said end being sharpened; a rod slidably mounted in said socket, said stem having oppositely disposed longitudinally extending slots communicating with said socket; a pin projecting peripherally in said rod and 25 engaging in said slots; an engagement member fixedly mounted on said stem; a collar embracing said stem and slidably thereon and engaging the ends of said pin; a spring positioned on said stem and engaged at one end 30 with said engagement member and at the other end with said collar for normally retaining said pin moved to one end of said slots; and a cutting head carried on the end 35 of said rod.

7. A tool of the class described, comprising; a stem having a socket formed in one end, the edges of said end being sharpened; a rod slidably mounted in said socket; a cutting head carried by said rod, said cutting head moving inwardly of said socket upon the inward movement of said rod in said socket; and resilient means for normally retaining 40 said cutting head projected exterior of said socket and yieldably resisting the inward movement of said rod relatively to said socket; and means for mounting said rod in said socket to effect rotation of said rod with said stem while not interfering with slidable 45 movement of said rod in said socket.

In testimony whereof I have signed the foregoing specification.

EDWARD H. ST. ONGE.
